TELEPHONE BASE WITH UNIT FOR READING
AND STORING DATA FROM CODED CARDS

John George Laycock Rhodes, Leatherhead, England,
assignor to Telephone Manufacturing Company Limited, London, England

Filed Sept. 9, 1970, Ser. No. 25,150

Claims priority, application Great Britain Mar. 10, 1971

Term of patent 14 years

Int. Cl. D14—03

U.S. Cl. D26—14

FIG. 1

FIG. 2

FIG. 3

FIG. 4

FIG. 5

FIG. 6

FIG. 1 is a perspective view of the telephone base with unit for reading and storing data from coded cards, showing my new design;

FIG. 2 is a front elevational view thereof;

FIG. 3 is a rear elevational view thereof;

FIG. 4 is a side elevational view thereof;

FIG. 5 is a top plan view thereof;

FIG. 6 is a perspective view of the telephone base with unit for reading and storing data from coded cards.

The broken lines are shown for illustrative purposes only.

I claim:

The ornamental design for a telephone base with unit for reading and storing data from coded cards, as shown and described.
